UNITED STATES PATENT OFFICE.

JOHN V. W. REYNOLDS, OF STEELTON, AND ARTHUR F. NELSON, OF HARRISBURG,
PENNSYLVANIA.

TIE-PLATE.

1,110,962.

Specification of Letters Patent.

Patented Sept. 15, 1914.

Application filed June 15, 1914. Serial No. 845,123.

To all whom it may concern:

Be it known that we, JOHN V. W. REYNOLDS and ARTHUR F. NELSON, citizens of the United States, residing, respectively, at 5 Steelton and Harrisburg, county of Dauphin, and State of Pennsylvania, have invented certain new and useful Improvements in Tie-Plates; and we do hereby declare the following to be a full, clear, and exact description of the invention, such as will enable others skilled in the art to which it appertains to make and use the same, reference being had to the accompanying drawings, and to letters or figures of reference marked 10 thereon, which form a part of this specification.

This invention relates to tie plates for railway track structures, and has for its object to provide a simple and efficient plate 20 adapted to be fastened to the tie and from which the rail can be removed without removing the fastening that holds the plate to the tie.

A further object is to give the plate such 25 a profile that it may be rolled in continuous lengths, which lengths are subsequently severed either transversely or obliquely to the length of the rolled shape to produce the individual tie plates.

Other and further objects of the invention will appear from the following description in connection with the accompanying drawings in which like parts are similarly designated and in which—

Figure 1 is an elevation of the tie plate made in accordance with this invention showing the rail held in place thereon. Fig. 2 is a plan view thereof, Fig. 3 is a plan view and Fig. 4 is a rear elevation of one of the 40 clips. Fig. 5 is an elevation of a modified form of tie plate, and Fig. 6 is a plan view of another form of clip.

Referring to Figs. 1 to 4, the tie plate consists of a central portion 1 provided with 45 a mid-rib 2 on its lower face, which central portion is flanked by grooves 3 located between said central or body portion 1 and securing flanges 4 having at their outer edges downwardly directed sharp ribs 5. The upper face of the plate has an unsymmetrical channel therein, one edge of which is provided with a vertical rib 6, the other edge of which is provided with a beveled 50 rib 7, said ribs being just beyond or

outside of the grooves 3 on the lower face 55 of the tie. As shown, the inner faces of these ribs 6 and 7 where they join the bottom of the channel, are about in vertical alinement with the outer walls of the grooves 3 in the underside of the plate. 60

The horizontal flanges 4 are provided with perforations 8 through which are passed lag screws, bolts, spikes, or similar devices 9 for securing the plate to its tie. The surface of the channel on the upper face 65 of the tie plate is provided at points on opposite sides of the rail foot with small ribs or lugs, *i. e.*, the beveled face 10 of the flange 7 is provided at intervals with ribs 11, and the bottom of the channel adjacent 70 the rib 6 is provided with ribs 12. These ribs are formed during the rolling operation by the shaping rolls. After the continuous shape has been rolled, it is cut transversely into plates of the width required for the 75 ties, the holes 8 are punched therein, as also are notches 13 extending from the side of the plate at the grooved portions 3, so that bolts 9 may be passed laterally into these notches with their heads engaging the 80 under-face of the plate in the grooves 3. These bolts pass up through clips 15 and 16. The clip 15 is provided with a rabbeted edge 17 for engaging the rail foot and a beveled edge 18 provided with serrations 85 forming notches or recesses 19, (Fig. 6), arranged to engage the ribs 11 on the beveled face of the rib 7.

The ribs 11 are preferably spaced apart at 90 distances which are multiples of the distances apart of the recesses 19 on the clips 15. The bolts 9 pass through the clips 15, a nut lock 20, and are held in place by the nuts 21. The clips 16 on the opposite side of the rail foot are also provided with a rabbeted 95 edge 22, and have an inclined lower face 23, a portion or all of which is serrated as shown, to provide indentations or recesses 24 for engagement with the serrations or ribs 12 at the side of the channel on the upper face of the plate and adjacent the rib 6. Bolts 9 pass through these clips and are secured by nut 21 and nut lock 20. In order to decrease the amount of metal in the central portion of the tie, one or more grooves 100 105 25 are rolled in the bottom of the channel. These grooves may be omitted when requirements demand it, or they may be increased

in number and size, it being sufficient to illustrate this invention to show two grooves symmetrically arranged with respect to the transverse center of the tie plate.

5 In Fig. 5 a similar tie plate is shown, the lower face of which is of the same configuration as shown in Fig. 3, but the upper face thereof is rolled symmetrically, that is to say, flange 6, is identical with the flange 7, 10 so that the clips used on both sides of the rail foot shall be identical in structure and configuration.

In Fig. 2 although the ribs 11 are shown at greater distances apart than the grooves 15 19 forming the serrations, it is obvious that instead of making these ribs 11 at distances which are multiple of the grooves in the clips, they may be made at the same distances apart. In applying the plate to a 20 tie by means of the fastenings 9, the central rib 2 and the cutting ribs 5 on the lower face of the plate are forced into the wood and assist in preventing movement of the plate with respect to the tie. These ties are usually treated ties and are reliable for a long 25 period of use. The ribs or lugs 11 and 12 when engaging the grooves 19 and 24 respectively, hold the clips which are forced by nuts 21, down between rail foot and 30 flanges 7 and 6, and prevent the bolts from working out of their notches 13.

The form shown in Fig. 5 has the advantage, that small adjustments of the rail may be readily made by slightly loosening a nut 35 21 on one side of the rail and tightening the nut on the other side, to compensate for wear of the rail or adjust alinement.

We claim—

1. A tie plate having a transverse channel 40 on its upper face for receiving the rail foot, a portion of the surface of which channel is provided with serrations, in combination with a rail foot engaging clip having an indented or serrated face for engagement with 45 said serrated portion.

2. A tie plate having a transverse rolled channel on its upper face included between

parallel ribs, one of said ribs having an inclined inner face provided with serrations, in combination with a clip having a rabbeted edge for engaging the rail foot and opposite beveled serrated edge, and a bolt for forcing the clip between said flange and the rail foot with its serrated face in engagement with a rib on the inclined face of said flange. 50 55

3. A tie plate, a body portion provided with grooves rolled in the under face thereof, lateral horizontal flanges, a channel rolled in its upper face between upwardly directed flanges beyond the grooves in its lower face, notches in the edges of the plate in said channel and grooves, said channel having ribs at each side of the rail seat, in combination with clips having grooved faces 65 arranged for engagement with said ribs and means to force said clips between the rail foot and sides of the channel. 60

4. A rolled tie plate blank having a channel in its upper face wider than the rail 70 foot to be supported therein, parallel grooves in its lower face, and lateral flanges.

5. A rolled tie plate blank having a channel on its upper faces wider than the rail-foot to be seated therein, said channel formed 75 between parallel flanges, parallel grooves on the underface of the plate substantially opposite the sides of the channel and horizontal securing flanges having cutting ribs on their lower outer edges. 80

6. A rolled tie plate blank having a channel in its upper face wider than the rail-foot to be seated therein and having serrations at each side thereof and beyond the portion of the channel on which the rail seats. 85

In testimony that we claim the foregoing as our invention, we have signed our names in presence of two subscribing witnesses.

JOHN V. W. REYNERS.
A. F. NELSON.
